UNITED STATES PATENT OFFICE.

PHILIP PHOEL, OF NEW YORK, N. Y.

DESIGN FOR A FINGER RING.

61,398.

Specification for Design. Patented Aug. 22, 1922.

Application filed April 30, 1921. Serial No. 465,838. Term of patent 3½ years.

To all whom it may concern:

Be it known that I, PHILIP PHOEL, a citizen of Holland, residing in the city of New York, New Dorp, borough of Richmond, in the county of Richmond and State of New York, have invented a new, original, and ornamental Design for Finger Rings, of which the following is a specification, reference being had to the accompanying drawings, forming a part thereof.

Figure 1 is a perspective view, and Fig. 2 is an edge elevation of a finger ring showing my new design, the ornamentation being forget-me-nots.

I claim:

The ornamental design for a finger ring, as shown and described.

PHILIP PHOEL.
